UNITED STATES PATENT OFFICE.

ERNEST R. HUNTLEY, OF LOS ANGELES, CALIFORNIA, ASSIGNOR TO INDUSTRIAL RE-
SEARCH CORPORATION, OF TOLEDO, OHIO, A CORPORATION OF DELAWARE.

ENGINE STARTER.

Application filed February 16, 1921. Serial No. 445,370.

This invention relates to starting mechanism for internal combustion engines or other engines which are normally non-self-starting.

- 5 The specific field of these starters is in connection with automobiles wherein an electric starting motor is employed which has a disconnectible drive connection to the fly-wheel of the engine.
- 10 An important object of the invention is the arrangement of a drive which automatically engages the engine gear when the motor is energized and which, when the engine begins to operate under its own power, is automatically disengaged, so that the employment of manual means, such as connecting rods, is made entirely unnecessary.
- 15 Another object of the invention is to provide means for taking up the shock, incident to the motor taking on the engine load, gradually and without any violent impact upon the motor parts, thereby preventing gear teeth breakage or any injury to the motor armature and bearings.
- 20 An important object also is the utilization of a gaseous fluid in the drive mechanism operative to gradually absorb the energy employed.
- 25 A further object is to remove, as far as possible, the necessity of using springs in the drive, inasmuch as they are subject to breakage through continued employment.

It is also an object of the invention to provide means for adjusting the working parts of the drive when the gear teeth of the drive and the engine fly-wheel meet end on end so that jamming of these parts is prevented.

Further objects and objects relating to economies of manufacture and details of construction will become apparent as I proceed with that modification of my invention illustrated in the accompanying drawings in which:—

Figure I is a view of the motor and drive properly associated with the engine member, portions of the drive and engine member being shown in section,

Figure II is a section taken through lines 2—2 of Figure I,

Figure III is a section taken through lines 3—3 of Figure I,

Figure IV is a section taken through lines 4—4 of Figure I, and

Figure V is a modification of the invention showing the utilization of a drive with-

in a hollow shaft upon which the armature is mounted.

Similar reference to numerals refer to similar parts throughout the drawings and the sections are taken looking in the direction of the arrows.

Referring to Figure I of the drawings I have shown a part 1 of the fly-wheel of an internal combustion engine, a portion of the periphery 2 of which is extended as at 3 and gear teeth 4 are cut in this extension. Positioned adjacent the fly-wheel gear, so that its shaft is in close proximity thereto, is an electric motor 5. This motor is designed to be attached preferably to the frame-work of the engine, by lugs 6 at one end of the motor, the body of the motor extending in a direction parallel to the engine shaft. The shaft 7 of the motor extends appreciably beyond its bearing 8 and is screw threaded for a considerable portion of its length exterior to the motor as indicated at 9. The end 10 of the shaft is cut so as to have a lesser diameter than the main portion of the shaft and within this end part 80 the machine screw 11 is adapted to have screw threaded engagement, the purpose of said screw being to hold in position a separable head or plunger element 12.

The plunger head 12 is adapted to have rigid engagement with the end of the shaft. For this purpose one face thereof is countersunk so as to fit over the end portion 10 of the shaft. The interior portion of the plunger head is of a lesser diameter and fits over the body of the machine screw 11. The other or outer face of the plunger 12 is also countersunk to receive the head 13 of the machine screw so that this face is perfectly plane. For a purpose hereinafter to be described the periphery of the plunger is grooved as at 14 and in this groove a wire shaped ring 15 is adapted to be positioned yieldingly, so that, while normally its diameter is greater than that of the plunger, pressure applied to the ring will cause it to contract into the groove.

Adapted to have screw threaded engagement with the threaded portion of the motor shaft is a sleeve element 16 which, for this purpose, is cut with an internal screw thread at the end thereof nearest to the motor. The outer end of the sleeve 16 is extended and enlarged to form a cylinder 17 possessing an internal diameter greater than 110

that of the screw threaded portion 16, and forming a chamber in which the plunger 12 is adapted to have sliding movement. At the inner end of the cylinder the plunger is limited in its movement by an annular shoulder 18 and at the other outer end it is limited by a plug 20 secured in the end of the cylinder. The portion of the cylinder adjacent the shoulder at the inner end thereof is enlarged sufficiently so that the wire ring 15 may expand beyond the diameter of the plunger. In consequence of this enlargement, movement of the plunger outwardly causes the wire ring to ride over an outer shoulder, formed at the junction of the cylinder proper, and this enlarged portion causing the ring to be compressed into the groove and thereby forming not only a tight, dust-proof bearing, but also means for preventing outward movement of the plunger unless appreciable force is applied to the motor shaft.

The normal position of the plunger is that in the inner end of the cylinder with the wire ring expanded. Within a relatively short distance from the outer face of the plunger, when in the normal position, an aperture 21 is cut in the cylinder wall, which aperture is adapted to be closed from the interior of the cylinder through the outward movement of the plunger, but when the plunger is in its normal position the aperture is unobstructed. Similarly, an aperture is formed in the plug 20 at the end of the cylinder and this latter aperture is adapted to be closed by means of a valve 22 fitted in a recess formed in the inner wall of the plug 20. This valve is formed of sheet metal stamping in the shape of a ring 23 into which ring extends a tongue 24 adapted to overlie the mouth of the aperture and to make closing contact thereupon.

Fitted on the inner end of the sleeve is a pinion 25 having gear teeth 26 cut in its periphery adapted to mesh with the fly-wheel teeth 4. In order to make ready engagement with the fly-wheel teeth the ends of the pinion teeth adjacent the fly-wheel teeth are chamfered and rounded as at 26'. The pinion 25 has limited sliding engagement upon the sleeve one limit of its movement, namely the inner limit, consisting in an annular band 28 fixed on the sleeve, and the other, or outer limit of its movement, being determined by a shoulder 29 formed in the circumference of the sleeve. Normally the pinion is held at the inner limit of its movement by means of springs 30 which are seated in the lateral projections 31 formed integrally with the middle portion of the sleeve. The pinion 25 is designed to have sliding movement relative to the sleeve 16 and to accomplish this result a series of projecting ribs axially extending along the outer surface of the sleeve are seated in cooperat-

ing channels formed on the interior of the pinion, which engagement permits axial movement of the pinion but does not permit relative movement of the pinion to the sleeve in the direction of rotation.

In brief the operation of this mechanism is to cause an engagement of a pinion with the gear wheel by virtue of the inertia of the pinion and the screw threaded connection with the motor shaft of the sleeve upon which it is mounted and then subsequently to transmit energy from the motor shaft to the gear wheel while the plunger is acting upon an elastic fluid. When the motor is energized and assuming that the motor shaft has a normal direction of rotation such as indicated by the curved arrow, the pinion will tend to move inwardly toward the motor into mesh with the fly-wheel. Assuming that enmeshment is initially made and subsequent to this initial engagement of the gear teeth, the aperture 21 is closed through the outward movement of plunger 12, thus preventing the free outward movement of the air, if such be the fluid employed. Whereupon, the movement of the plunger and consequently the meshing movement of the gear teeth and pinion is hindered to a degree determined by the amount of air leakage from the air chamber, the pressure in said chamber being further heightened through the closure of the aperture, the tongue 24 of the valve being seated over the aperture through the increase of pressure in the chamber. Consequently force is transmitted from the motor shaft to the sleeve and pinion in a yielding manner depending upon the leakage about the plunger. As soon as the plunger is moved to its outer limit and the pinion is in full mesh with the gear wheel, the latter, which has already been receiving energy, takes on the full force of the motor.

In the event that the pinion 27, when moving axially toward the gear wheel, fails to make proper enmeshment with the gear wheel, the end of the pinion teeth abutting those of the gear wheel, the pinion slides on the sleeve outwardly compressing springs 30 and at the same time slightly rotating, and this movement is continued until the rotation of the pinion is sufficient to clear the gear teeth, at which time complete enmeshment will take place. This provision is made necessary due to the fact that unless some yield were provided for the contingency where the gear teeth fail to mesh at certain times, jamming of these parts could occur resulting either in breakage or improper operation of the starting device, either possibility being undesirable.

Subsequent to the starting of the engine, the acceleration given the pinion by the highly accelerated fly-wheel is sufficient to screw it outwardly along the motor shaft

and out of mesh with the gear teeth. During this outward movement of the pinion instead of compression in the cylinder 17, there is a tendency toward a slight vacuum which causes the tongue 24 of the plug aperture to move away therefrom, thereby permitting atmospheric pressure to be maintained in the cylinder. Also on the side of the plunger adjacent the screw threads approximate atmospheric pressure is maintained by means of the aperture 21 and through leakage around the screw threads between the sleeve and the motor shaft. It is therefore apparent that the plunger may move readily and freely toward the inner limit of its movement to a point where the ring spring member slips into the enlarged portion of the cylinder and is retained therein until the force, such as the starting of the motor, is applied sufficiently to cause the spring to ride over the outer adjoining shoulder within the cylinder.

In the modification shown in Figure V the armature shaft is hollowed and the pinion, instead of being slidably mounted on a sleeve, is splined upon a solid drive shaft axially slidable in the armature shaft as indicated at 50. The pinion is held to one limit of its movement by springs 51 seated within cavities 52 formed in the outer wall of the pinion, the projecting ends of the said springs having bearing against a washer 53 secured to the shaft ends by means of a nut 54. At the other end of the sleeve, the shaft is screw threaded and carries a plunger element fastened to the end of the shaft by means of machine screw in the manner hereinbefore described with reference to the preferred form. A bushing is fixed to the interior of the hollow armature shaft and this bushing is internally threaded to receive the threaded portion of the drive shaft. The end of the shaft adjacent the plunger is closed by a plug 55 which has an aperture 56 and valve 57 similar to that previously described. The hollow shaft is mounted in bushings 58 and 59 which rest in bearings 60 and 61 and at the end of the hollow shaft, opposite to that at which the pinion is placed, a dust protecting cap 62 is inserted.

On the drive shaft near the pinion a groove 63 is formed in which is seated a ring spring 64 adapted to expand resiliently against the inner wall of the hollow shaft of the armature. In the normal disengaged position of the pinion this resilient element expands into an annular groove 65 formed in the wall of the hollow shaft so that unless some special force is exerted on the driving shaft such as that due to the starting of the motor, this shaft will ordinarily not be moved from its normal disengaged position.

In this modification of my invention, no utilization is made of the aperture of the plunger cylinder as shown at 21 in Figure

I, the fittings in this case being made sufficiently loose so that air leakage to a proper extent may occur.

The operation of the modification above described is practically identical to that described with reference to the preferred form, energization and rotation of the motor carrying the sleeve element screws the drive shaft into the motor against the cushioning effect of the air enclosed in the cylinder. In this arrangement the movement of the plunger is not slowed down appreciably prior to the initial engagement of the pinion to the fly-wheel but subsequent to this engagement considerable resistance is offered to the movement of the plunger and hence energy is transferred directly from the armature to the fly-wheel in gradually increasing amounts until, when the plunger has moved to its limit and the pinion is in complete engagement with the fly-wheel, the full power of the motor is applied. The starting of the engine serves to screw the drive shaft out of the motor until the spring ring slips into the groove cut on the interior of the hollow motor shaft, there retaining the shaft until the next starting movement is inaugurated.

I am aware that the particular embodiment of my invention above described and illustrated in the accompanying drawings is susceptible of considerable variation without departing from the spirit thereof, and therefore I desire to claim my invention broadly as well as specifically as indicated by the appended claims.

Having thus described my invention, what I desire to claim for Letters Patent is:—

1. A starting device for engines comprising a motor having an extended shaft, a portion of which is screw threaded; a sleeve, closed at one end and cut with an internal screw thread at the other end, said sleeve having screw threaded engagement with the shaft; a plunger head fixed to the shaft end and adapted for sliding movement within the sleeve; means associated with the sleeve operative to hinder movement of the plunger head within the cylinder; and a pinion mounted on the sleeve.

2. In combination with an extended motor shaft, a portion of which is screw threaded; a plunger head, fixed to the end of the shaft; a sleeve having an internal screw thread in one end of the sleeve, said sleeve being screw threaded on the shaft and having sliding engagement with the plunger head; a plug at the end of the sleeve opposite from the screw threaded end, said plug having an aperture therein; a valve associated with the aperture operative to hinder passage of air from within the sleeve; a pinion mounted on the sleeve and slidably relative thereto; and yieldable elements seated on the sleeve and adapted for holding the pinion against sliding movement.

3. In a drive mechanism, the combination of a motor shaft; a sleeve mounted on the shaft for relative movement thereto and rotary movement therewith; a plunger head fixed to the shaft at its end and adapted to have sliding movement within the sleeve; an apertured plug in the sleeve end adjacent the plunger, said plug, plunger and sleeve forming a fluid chamber; a valve secured adjacent the aperture in the plug, said valve being effective to permit free movement of fluid into the chamber and to hinder fluid movement from within the chamber; and a drive wheel mounted on the sleeve and adapted to have sliding engagement therewith. 55
4. In a drive mechanism, the combination of a motor shaft; a sleeve mounted on the shaft for relative movement thereto and rotary movement therewith, said sleeve having an aperture formed therein; a plunger head fixed to the shaft at its end and adapted to have sliding movement within the sleeve thereby closing the sleeve aperture; 60
- 20 25 an apertured plug in the sleeve end adjacent the plunger, said plug, plunger and sleeve forming a fluid chamber; a valve secured adjacent the aperture in the plug, said valve being effective to permit free movement of fluid into the chamber and to hinder fluid movement from within the chamber; and a drive wheel mounted on the shaft and adapted to have sliding engagement therewith. 65
5. In a starter mechanism for engines the combination of a shaft; a sleeve mounted on the shaft for both rotary and axial movement relative thereto; a plunger fixed on the shaft end and adapted to have sliding movement within the sleeve; a plug in the sleeve end; apertures in the plug and sleeve, said apertures being closed by movement of the plunger toward the plug; and a drive wheel mounted on the sleeve. 70
- 35 40 45 6. In a starter mechanism for engines the combination of a shaft; a sleeve mounted
- on the shaft for both rotary and axial movement relative thereto; a plunger fixed on the shaft end and adapted to have sliding movement within the sleeve; a plug in the sleeve end; apertures in the plug and sleeve, said apertures being closed by movement of the plunger toward the plug; a drive wheel slidably mounted on the sleeve; and means tending to hold the pinion at one limit of its sliding movement. 75
7. In a starting device for engines the combination of a motor shaft; a sleeve mounted on the shaft for rotary and axial movement relative thereto; a cylinder extending from and integral with said sleeve, said cylinder having an aperture in its wall adjacent the point of connection with the sleeve, and a second aperture in its end; a valve adjacent the end aperture; a plunger secured to the shaft end adapted to close the wall aperture directly by its movement and to close the end aperture indirectly by compression of the fluid contents of the cylinder; and a drive wheel on the sleeve. 80
8. In a starting device for engines the combination of a motor shaft; a sleeve mounted on the shaft for rotary and axial movement relative thereto; a cylinder extending from and integral with said sleeve, said cylinder having an aperture in its wall adjacent the point of connection with the sleeve, and a second aperture in its end; a valve adjacent the end aperture; a plunger secured to the shaft end adapted to have a compression stroke and an expansion stroke 85 in the cylinder; said plunger being operative to close first the wall aperture and subsequently the end aperture in a compression stroke, and to open the end aperture and subsequently the wall aperture in an expansion stroke; and a drive wheel slidably mounted on the sleeve. 85

In testimony whereof, I affix my signature.

ERNEST R. HUNTLEY.
